[57] CLAIM

The ornamental design for a combined dashboard map holder and adjustable light, as shown and described.

DESCRIPTION

FIG. 1 is a front elevational view of a combined dashboard map holder and adjustable light showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a perspective view thereof.

The power cord in FIGS. 1 through 4 and 7 has been shown broken away for the purpose of indicating indeterminate length.
